UNITED STATES PATENT OFFICE

ALFRED L. RUTHVEN, OF ROCHESTER, NEW YORK

AUTOMANUAL RESETTING DEVICE

Application filed November 1, 1928. Serial No. 316,538.

The present invention relates to automatic train control, and more particular to resetting, clearing or restoring devices such as are provided for resetting the control apparatus after an automatic stop has been made in order that the train or vehicle may proceed, this application disclosing improvements over the device disclosed in my co-pending application Serial No. 274,274, filed

10 May 1, 1928.

It is the object of the present invention to provide a resetting device which may be conveniently operated by the engineman without requiring him to leave his regular position, and which device will not function unless the train or vehicle is at rest, so that the device cannot function while the train or vehicle is in motion even though the engineman makes effort to reset the apparatus or 20 to prevent an automatic stop, the device being improved in order to make same thoroughly safe and reliable.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a sectional view of a resetting device embodying the improvements, portions being shown in elevation and the electrical circuit being shown diagrammatically, with the parts in normal position.

Fig. 2 is a view of the device shown in Fig. 1 in active position for resetting, portions being shown in section and portions in elevation.

Fig. 3 is a sectional view corresponding with Fig. 1 and illustrating a modified construction.

Fig. 4 is a view corresponding to Fig. 2 showing the modified device of Fig. 3.

Referring to Figs. 1 and 2, which show one embodiment of the invention, a cylinder 7 is mounted for swinging movement on a hinge rod 8 mounted within a housing or

hood 9 which has a flange 10 or other suitable means for attaching it to the frame or body of the locomotive or other vehicle, whereby the cylinder may swing in either direction.

A piston 11 works in the cylinder and has a tubular stem 12 slidable through the free end of the cylinder, and the protruding end of the stem 12 has a shoulder or valve head 13 to seat against the lower end or head of the cylinder to prevent the escape of air or pressure fluid when the piston 11 is moved to its uppermost position, as seen in Fig. 1.

A contact member or finger 14 is slidable in the stem 12 and has a piston 15 working within a cylinder chamber 16 provided in the cylinder 11 and stem 12, and the stem 12 has vents 17 below the piston 15 to permit the air to flow into and out of the chamber 16 below the piston 15. The finger 14 has a hole or bore 18 extending from the upper surface of the piston 15 to a point close to the lower protruding end of the finger 14, in order that the wearing off or breaking of the finger 14 will permit the air to escape from above the pistons 11 and 15, so that the defect in the finger 14 may be detected and failure of the device avoided.

The finger 14 is adapted to contact with a wheel 19 of the locomotive or vehicle, or with any other moving part, or may be arranged to contact with a rail of the track.

Said finger may be of frictional material in order to prevent slippage between it and the part with which it contacts.

An insulated contact 20 is mounted on the bottom of the cylinder 7 for the engagement of a contact 21 carried by and insulated from the piston 11, and a contact arm 22 is hingedly mounted on the piston 11 in electrical connection with the contact 21 for engaging a contact 23 carried by and insulated from the top of the cylinder 7. The contact 21 is normally raised away from the contact 20, as seen in Fig. 1, with the arm 22 swung downwardly away from the contact 23, and when the pistons 11 and 15 are moved downwardly, the finger 14 contacting with the wheel or member 19 will be arrested, while the piston 11 moves downwardly to bring the contact 21 against the contact 20. The pis-

ton 15 has a stud 24 thereon which will contact with the arm 22, due to the downward movement of the piston 11 relatively to the piston 15 and finger 14, thereby swinging 5 the arm 22 upwardly so that it engages the contact 23. This closes the electrical connection between the contacts 20 and 23.

The cylinder 7 has an arm 25 carrying an insulated contact 26 normally engaging an 10 insulated contact 27 carried by the hood 9 when the cylinder 7 is in neutral or intermediate position.

The resetting circuit includes the wire or conductor 28 connected to the contact 27, a 15 wire or conductor 29 connecting the contacts 23 and 26, and a wire or conductor 30 connected to the contact 20. With the parts in normal position, as seen in Fig. 1, the circuit is broken at the contacts 20 and 23.

20 Suitable springs 31 are disposed between the arm 25 and hood 9 to maintain the cylinder 7 yieldingly in neutral or intermediate position, with the contacts 26 and 27 together, and the cylinder 7 may be swung in 25 either direction, which will immediately remove the contact 26 from the contact 27 so as to interrupt the resetting circuit at this point.

The cylinder 7 has fluid passages 32 and 33 leading to the upper and lower ends of 30 the cylinder chamber, and communicating with tubes or pipes 34 and 35, respectively, connected with a manually operable valve 36 to which is connected a compressed air or pressure fluid supply pipe 37 and a discharge 35 vent 38. The valve 36 is preferably arranged to be conveniently operated by the engineer- man.

In the normal position of the valve 36 it 40 connects the pipe 35 with the pipe 37 and the pipe 34 with the atmosphere, so that the pressure fluid or air flowing into the lower portion of the cylinder 7 will move the piston 11 upwardly, thereby removing the contact 21 from the contact 20. The shoulder or 45 valve portion 13 seats against the bottom of the cylinder to prevent the escape of air, and the arm 22 swings downwardly by gravity away from the contact 23, so that the resetting circuit is broken at two points.

50 In order to reset the vehicle equipment, the valve 36 is operated to connect the pipe 34 with the compressed air supply pipe 37 and to connect the pipe 35 with the atmosphere. The air entering the upper end of the cylinder will depress the pistons 11 and 15, thereby moving the finger 14 against the wheel or part 19, and although the finger 14 is stopped the piston 11 is moved downwardly further to bring the contact 21 against the 55 contact 20 as seen in Fig. 2, and the arm 22 engaging the stud 24 will be swung upwardly, by the movement of the piston 11 relatively to the piston 15, into engagement with the contact 23, thereby closing the resetting circuit.

It is compulsory, however, that the locomotive or vehicle be at rest in order that the resetting may be accomplished, for if the vehicle is in motion, the finger 14 coming into contact with the wheel or part 19, will immediately swing the cylinder 7 in the corresponding direction before the piston 11 is moved downwardly sufficiently to bring the contact 21 against the contact 20.

The contact 26 will therefore be moved 75 away from the contact 27 to open the circuit at the contact 27 before the circuit can be closed at the contacts 20 and 23.

Moreover, if the finger 14 is worn away or broken off, then, instead of assuming the 80 position shown in Fig. 2, it will be moved downwardly further, so that the stud 24 cannot raise the arm 22 against the contact 23, it being obvious in referring to Fig. 2 that if the lower end of the finger 14 is worn away or broken off the finger can naturally move downwardly further before being stopped by the wheel or member 19, and the stud 24 being moved downwardly further will not be in a position to swing the arm 22 90 against the contact 23. Furthermore, the hole or passage 18 being opened will permit the air to escape, whereby the noise of the escaping air will give a signal so that the defect in the finger 14 may be detected.

The piston 15 being moved downwardly by air pressure will bring the finger 14 into 95 tight contact with the wheel or part 19, so as to assure of the cylinder 7 being swung or displaced before the resetting circuit is closed, 100 should the vehicle be in motion.

When the valve 36 is released or restored to normal position, the piston 11 is raised as hereinbefore described, thereby breaking the circuits at the contacts 20 and 23, and the piston 15 and finger 14 are lifted with the stem 12.

Figs. 3 and 4 illustrate a modification, including a contact arm 22^a hingedly connected with the top of the cylinder 7' to be raised against the contact 23' for connecting the wires or conductors 29' and 30' which are connected to said arm and contact, respectively.

The arm 22^a normally swings downwardly 115 away from the contact 23', as seen in Fig. 3, and when the piston 11' is moved downwardly, as seen in Fig. 4, the arm 22' which is hingedly mounted on the piston 11' is raised by the stud 24' of the piston 15' and engages the arm 22^a, thereby swinging said arm 22^a 120 upwardly against the contact 23', to close the resetting circuit.

By using the arm 22^a and contact 23', the use of the contacts 20 and 21 hereinbefore described is avoided, but the circuit is only broken at one point (contact 23').

Having thus described the invention, what is claimed as new is:

1. A resetting device for automatic train 130

- control comprising a cylinder, two relatively movable pistons movable in said cylinder, one piston having a portion to contact with another part to limit the movement of said piston, means for supplying pressure fluid into said cylinder to move both of said pistons, and means for closing a resetting circuit constructed and arranged to be operated by the predetermined and relative movement of said pistons with the firstnamed piston limited in its movement by said part. 5
2. A resetting device for automatic train control comprising a cylinder, two relatively movable pistons movable in said cylinder, one piston having a portion to contact with another part to limit the movement of said piston, means for supplying pressure fluid into said cylinder to move both of said pistons, and means for closing a resetting circuit including an arm hingedly mounted on one of said pistons and having a portion on the other piston by the predetermined and relative movement of said pistons with the firstnamed piston limited in its movement by said part, so as to move said arm to operative position, and means for breaking said circuit when said cylinder is moved from normal position. 10
3. A resetting device for automatic train control comprising a cylinder, a piston movable in said cylinder, a second piston movable in the firstnamed piston and having a portion to contact with another part to limit the movement of the second piston, means for supplying pressure fluid to said cylinder to move said pistons, and means for closing a resetting circuit constructed and arranged to be operated by the predetermined and relative movement of said pistons with the second piston limited in its movement by said part. 15
4. A resetting device for automatic train control comprising a cylinder, a piston movable in said cylinder, a second piston movable in the firstnamed piston and having a portion to contact with another part to limit the movement of the second piston, means for supplying pressure fluid to said cylinder to move said pistons, and means for closing the resetting circuit including an arm hingedly mounted on the firstnamed piston and a portion on the second piston to contact with the arm for swinging the arm to operative position by the predetermined and relative movement of said pistons with the second piston limited in its movement by said part. 20
5. A resetting device for automatic train control comprising a cylinder mounted for movement, two relatively movable pistons movable in said cylinder, one piston having a portion to contact with another part for moving said cylinder from a normal position, means for supplying pressure fluid to said cylinder to move said pistons, and means for closing a resetting circuit and arranged to be operated by the predetermined and relative movement of said pistons with the firstnamed piston limited in its movement by said part. 25
6. A resetting device for automatic train control comprising a cylinder mounted for movement, two relatively movable pistons movable in said cylinder, one piston having a portion to contact with another part for moving said cylinder from a normal position, means for supplying pressure fluid to said cylinder to move said pistons, and means for closing a resetting circuit including an arm hingedly mounted on one of said pistons for the contact of a portion on the other piston by the predetermined and relative movement of said pistons with the firstnamed piston limited in its movement by said part, so as to move said arm to operative position, and means for breaking said circuit when said cylinder is moved from normal position. 30
7. A resetting device for automatic train control comprising a cylinder mounted for movement, a piston movable in said cylinder, a second piston movable in the firstnamed piston and having a portion to contact with another part for moving said cylinder from normal position, means for supplying pressure fluid to said cylinder to move said pistons, and means for closing a resetting circuit constructed and arranged to be operated by the predetermined and relative movement of said pistons with the firstnamed piston limited in its movement by said part, and means for breaking said circuit when said cylinder moves from normal position. 35
8. A resetting device for automatic train control comprising a cylinder mounted for movement, a piston movable in said cylinder, a second piston movable in the firstnamed piston and having a portion to contact with another part for moving said cylinder from normal position, means for supplying pressure fluid to said cylinder to move said pistons, and means for closing a resetting circuit including an arm hingedly mounted on the firstnamed piston and a portion on the second piston to contact with the arm for moving said arm to operative position by the predetermined and relative movement of said pistons with the second piston limited in its movement by said part, and means for breaking said circuit when said cylinder is moved from normal position. 40
9. A resetting device for automatic train control comprising a cylinder, two relatively movable pistons movable in said cylinder, one piston having a portion to contact with another part to limit the movement of said piston, means for supplying pressure fluid into said cylinder to move both of said pistons, and means for closing a resetting circuit constructed and arranged to be operated by the predetermined and relative movement of said pistons with the firstnamed piston limited in its movement by said part. 45

pistons with the firstnamed piston limited in its movement by said part, the firstnamed piston and said portion thereof having a hole to permit the escape of pressure fluid if said portion is broken or worn off.

10. A resetting device for automatic train control comprising a cylinder, a piston movable in said cylinder, a second piston movable in the firstnamed piston and having a portion to contact with another part to limit the movement of the second piston, means for supplying pressure fluid to said cylinder to move said pistons, and means for closing a resetting circuit constructed and arranged 15 to be operated by the predetermined and relative movement of said pistons with the second piston limited in its movement by said part, the second piston and said portion thereof having a hole to permit the pressure fluid to escape if said portion is broken or worn off.

11. A resetting device for automatic train control comprising a cylinder, a piston movable in the cylinder and having a stem projecting therefrom, a second piston movable in the firstnamed piston and having a finger projecting from said stem to contact with another part, means for supplying pressure fluid to the opposite ends of the cylinder to move the firstnamed piston in opposite directions and to move the second piston to project said finger, said stem having a portion seatable against the cylinder to prevent the escape of pressure fluid when the firstnamed piston is moved to retract said stem, and means for closing a resetting circuit constructed and arranged to be operated by the predetermined and relative movement of said pistons with said finger contacting with said part and limiting the movement of the second piston.

12. A resetting device for automatic train control comprising a movably mounted cylinder, a piston movable in said cylinder and having a stem projecting therefrom, a second piston movable in the firstnamed piston and having a finger projecting from said stem to contact with another movable part for moving said cylinder from a normal position, means for supplying pressure fluid into the opposite ends of said cylinder for moving the firstnamed piston to retract said stem and for moving both pistons to project said stem and finger, the second piston and finger having a hole to permit the escape of pressure fluid if said finger is broken or worn off, said stem having a portion to seat against the cylinder when said stem is retracted to prevent leakage of pressure from the cylinder, and means for closing a resetting circuit including an arm hingedly mounted on the firstnamed piston and a portion on the second piston to contact with the arm and swing it to operative position when the pistons are moved to

project said stem and finger with the finger limited in its movement by said part.

In testimony whereof I hereunto affix my signature.

ALFRED L. RUTHVEN.
